UNITED STATES PATENT OFFICE.

FRANK C. MARQUARDT, OF BROOKLYN, NEW YORK, ASSIGNOR TO AMERICAN BANK
NOTE COMPANY, OF NEW YORK, N. Y., A CORPORATION OF NEW YORK.

SHEET-DELIVERY MECHANISM FOR PRINTING MACHINES.

Application filed February 9, 1922. Serial No. 535,161.

To all whom it may concern:

Be it known that I, FRANK C. MARQUARDT, a citizen of the United States, residing at the borough of Brooklyn, in the city of New York, county of Kings and State of New York, have invented certain new and useful Improvements in Sheet-Delivery Mechanisms for Printing Machines, of which the following is a specification, reference being had therein to the accompanying drawings, which form a part thereof.

My invention relates to sheet delivery mechanisms for printing machines, and more particularly to a type thereof adapted for use upon rotary printing machines.

In a machine embodying my invention, each sheet as it receives its impression from the printing couple, is received by a travelling gripper mechanism and conveyed thereby and delivered to a collecting table upon which succeeding sheets are stacked, there being a sufficient elapsed interval between the making of the impression and the delivery of the printed sheet to said table to permit a sufficient drying or oxidation of the ink to avoid likelihood of offsetting from one sheet to another, and thus permit the use of insert and offset sheets to be dispensed with.

While the sheet is being conveyed from the printing couple to the collecting table, it is subject to no pressures and has no extended areas contacting with the conveying means which might tend to smut the imprint.

The gripper mechanism above referred to consists of a sequence of bars carried by a continuously travelling belt or chain and so spaced apart as to successively cooperate with the gripper mechanism of the impression cylinder, suitable means being provided for actuating the gripper fingers associated with each of said bars, in a timely manner to engage the sheet at the impression cylinder and to release the sheet at the collecting table, a disengaging mechanism being employed adjacent the gripper fingers to ensure the separation of the sheet from the travelling gripper mechanism and its falling upon the collecting table in approximately the proper position to ensure the desired neat stacking of succeeding sheets.

The collecting table is so constructed that it may be lowered from time to time as the stack of sheets accumulates thereon, there being grouped about the point of the release of the sheet by the gripper mechanism, automatically acting straightening devices so constructed and arranged as to move away from the stack during the delivery of a sheet to the table, to provide the proper clearance, and subsequently engage the edges of the sheet and bring them in substantial accord with the edges of the sheets of the adjacent portion of the stack. These straightening devices operate only adjacent the top of the stack, the collecting table having movement away from them when adjusting it to accommodate it to the increase in the height of the stack.

While the stack itself is lowered manually, I provide means whereby power may be applied thereto to restore it to its high position when a stack of printed sheets has been removed therefrom and it is desired to start a new stack.

The invention consists primarily in a delivery mechanism for printing machines embodying therein the combination with a printing couple, of a collecting table spaced away therefrom, a conveyer mechanism including therein endless chains, a plurality of platen bars carried thereby, gripper fingers associated with each platen bar, guiding means for said chains consisting of sprocket wheels adjacent said printing couple, sprocket wheels below said first named sprocket wheels and adjacent opposite ends of said table, and intermediate sprocket wheels, whereby said chains have an upper direct reach, a lower return reach, and a substantially horizontal reach parallel with and above said table, in which last reach the position of said grippers will be reversed in position as compared with when they are passing along said upper direct reach, actuating means for said gripper fin-

gers operative as said chains are passing from said lower return to said upper direct reach, and as said chains are passing from said reach parallel with the table to 5 said return reach respectively, and means whereby lineal traverse is imparted to said chains in synchronism with a peripheral traverse of the members of the printing couple; and in such other novel features of 10 construction and combination of parts as are hereinafter set forth and described, and more particularly pointed out in the claims hereto appended.

Referring to the drawings,

15 Fig. 1 is a view of a delivery mechanism embodying my invention, with a portion of the printing couple shown in connection therewith;

Fig. 2 is a side view upon a larger scale of 20 the portion of said mechanism adjacent the collecting table;

Fig. 3 is an end view thereof;

Fig. 4 is a perspective view of one of the 25 gripper bars and its associated gripper and gripper actuating means; and

Fig. 5 is a vertical section on the line 5—5 of Fig. 3.

Like numerals refer to like parts throughout the several views.

30 In the embodiment of my invention shown in the drawings, I have indicated a portion of a form or plate cylinder at 10, and a portion of an impression cylinder associated therewith at 11, the details of other portions 35 of the printing machine being immaterial to my present invention, it being practicable to use the delivery mechanism of my invention with either a perfecting or a nonperfecting press because of the small area of the portions 40 of the delivery mechanism which engage the sheet at any time between the making of an impression and the delivery of a sheet to the collecting table.

45 Adjacent the printing couple is a shaft 12 having sprocket wheels 13 adjacent the opposite ends thereof, said shaft also carrying a gear wheel 14 in mesh with a gear wheel carried by said impression cylinder, through which gearing the delivery mechanism is actuated in synchronism with the printing couple.

50 Mounted in suitable frames spaced away from said printing couple a sufficient distance to secure the desired drying action of the ink, is a vertically movable collecting 55 table 15 which will be more fully described hereinafter, adjacent which table is a shaft 16 counter to the shaft 12 and carrying adjacent the opposite ends thereof, sprocket 60 wheels 17.

55 Passing about the pairs of sprocket wheels 13 and 17 are two continuous sprocket chains 18 and 19. For convenience of expression said chains may be considered as having an upper direct reach between the two sets of

sprocket wheels 13 and 17, adapted to convey printed sheets from the printing couple toward said table, a horizontal reach between the sprocket wheels 17, and about sprocket wheels 20, and extending parallel 70 with and above the collecting table 15, but below the direct reach and a lower return reach passing over the guide sprocket wheels 21 and 22.

The portion of the direct reach adjacent 75 the table 15 is arranged on a decline as shown, so as to bring the horizontal reach closely adjacent the point of delivery of a sheet upon said table, guide sprockets 23 carried by a shaft 24 being provided at the top 80 of the declining portion of said reach.

Carried by the chains 18 and 19 at spaced intervals, which are determined by the circumference of the impression or other cylinder from which the printed sheets are collected, are a plurality of gripper mechanisms, each of which is identical in construction and mode of operation with every other, so that a description of but one of such 90 mechanisms is essential.

Each of the gripper mechanisms above referred to consists of end fittings 25 and 26 secured to opposite links of the chains 18 and 19 in a manner to have no movement in relation to said links. Carried by said fittings, 95 below the inner face of the chain, is a fixed platen rod 27 having an elevated platen 28 which is in, or slightly above, the outer face of the chain. Pivotaly mounted in the fittings 25 and 26 is an oscillatory shaft 29 parallel with the rod 27 and carrying a plurality of gripper fingers 30 adapted to operatively engage the platen 28 upon said rod 27. Acting upon the shaft 29 are torsion springs 31 adapted to normally engage the 100 gripper fingers 30 with the gripper platen 28.

The gripper rod 29 has, adjacent the opposite ends thereof, crank arms 32 carrying anti-friction rollers as shown, which rollers 110 are adapted to engage fixed cams 33 adjacent the impression cylinder 11, and fixed cams 34 adjacent the rear edge of the table 15 in the direction of movement of the horizontal reach of said chain. In this manner 115 the gripper fingers will be automatically opened and closed to receive the sheet from said impression cylinder, and will be opened when said gripper mechanism approaches the limit of its movement above the table 15, 120 while it is in the horizontal reach of the sprocket chain above said table, the printed sheet being firmly held by said grippers at all times between the closing of the gripper fingers and their opening to permit the 125 printed sheet to be delivered to the table.

To ensure the proper turning of the sheet as it approaches the table 15, I provide the shaft 16 with a sequence of wheels 35, the peripheries of said wheels having therein a 130

recess 35^a adapted to receive the gripper mechanisms and keep the plane of the gripper platen 28 substantially flush with the perimeter of said wheels, thus causing the paper to pass about said wheels with a wide bend to prevent any possible mutilation or wrinkling of the sheet, the speed of the gripper mechanism being sufficiently high to prevent the straightening of the sheet 10 until it is in substantially its entirety, above the table 15.

To support the paper while it is being conveyed from the printing couple to adjacent the wheels 35, I provide a sequence of 15 movable supports, preferably consisting of fine wires 36 passing about the driving roller 37 and guide rollers 38 and 39, the latter of which is adjacent the printing couple. These wires 36 are actuated at the same peripheral speed as the chains 18 and 19 by means of the sprocket and chain drive 40 between the roller 37 and the shaft 16. By this construction, I not only avoid rubbing contact between the wires 36 and the 20 printed sheet, but by using round wires, secure a contact area between same and the sheet so small as to permit contact of atmospheric air with substantially the entire surface of the sheet and avoid any possible offsetting from the sheet to the said wires which are non-absorptive.

The distance between the shaft 12 and the shaft 16 is sufficiently great to ensure a 25 substantial drying of the ink or a sufficient oxidation thereof, to permit the freshly printed surface of the sheet to be laid upon the preceding sheet on the table 15, without any likelihood of offsetting from one sheet to the other, and this condition prevails 30 whether the delivery mechanism is used with a perfecting or non-perfecting press.

To ensure the desired tautness in the wires 36, I provide a takeup and guide roller 41 carried by adjustable links 42 arranged upon opposite sides of the machine and each acted upon by a screw 43. To prevent sagging of the chains, I provide upon opposite sides of the machine, vertically extending guides 44 positioned between the guide sprockets 20 and 21, and similar guides 45 extending between the sprockets 13 and 23.

Mounted above the horizontal reach of the chains 18 and 19 is a crank shaft 46 carrying a plurality of light presser fingers 47 adapted to be brought into engagement with the sheet being transported by the gripper mechanism, and force it toward the stack of sheets upon the table 15 substantially 50 simultaneously with the disengagement of the fingers of said gripper mechanism from the forward edge of the sheet. Said crank shaft 46 is actuated by the bell crank lever 48, one arm of which carries a roller engaging the cam 49 upon the shaft 16 and the

other arm of which is connected by the pitman 50 with the crank of said crank shaft 46.

Said pitman 50 passes through a bracket 51 and is acted upon by the spring 52 acting between said bracket, and a collar 53 upon said pitman, to restore the presser fingers 47 to their inoperative, elevated position and hold the roller upon the lever 48 in engagement with the cam 49. 75

The table 15 is sustained by the chains or other suspension means 54 connected with opposite sides of the table at 55, and the other end of which is connected to winches 56. The table 15 is adapted to be lowered 80 by means of the winches 56 and said chains 54 through the medium of the worm wheel 57, the co-operating worm shaft 58, the entrained gears 59 and 60 carried by said shaft, and by the shaft carrying the hand wheel 61 respectively, and is adapted to be raised under power when a stack of printed sheets of a maximum height after being accumulated thereon, has been removed preparatory to a continued run of the press with which 85 the delivery mechanism is associated. This restoring mechanism for the table consists of the bevelled gear 62 carried by the shaft of the guide sprocket wheel 20, a bevelled gear 63 adapted to be moved in and out of mesh with said gear 62 by the controlling handle 64, and a chain and sprocket mechanism 65 connecting the shaft of said gear 63 with the shaft carrying the hand wheel 61 and the gear 60. 90

The table 15 has a considerable range of vertical movement to permit a continued run of the machine without the necessity for stoppage to remove the printed sheets from the table. As the stack of sheets attains a 100 substantial height, the dead weight of the load upon the table is considerable, so that it is essential to not only provide suspension means of sufficient strength to sustain this load, but to guide the table in its vertical 105 movement in a manner to prevent the tilting thereof and also to provide straightening devices entirely independent of the table and acting at all times adjacent the top of the stack, to ensure a proper stacking of the 110 sheets as they are delivered to the table and avoid likelihood of the falling of the stack 115 due to its becoming out of plumb.

The table 15 is provided, upon opposite sides thereof, with laterally extended slides 120 66 and 67 adapted to enter slide ways in the side frames of the machine, the slides being spaced apart as shown to afford clearance for the chains 54. In addition to the spaced slides upon each side of the table 15, I provide a plurality of anti-friction rollers 125 68-69 projecting from the outer face of said slides and adapted to engage the edge of the slide ways in which the slides move, said rollers of each set being so spaced with 130

- relation to each other as to ensure against any tilting action of the table laterally thereof, the slides 66 preventing forward and backward tilting of the table.
- 5 The rollers 68-69 also ensure ease in the movement of the table. While other means may be provided to ensure the desired parallel movement of the table 15, that described has been found very effective in use.
- 10 The chains 54 in passing from the winches 56 to the point of connection 55 with the table 15, pass about the guide sprockets 70-71 carried by each side frame of the machine.
- 15 Mounted in the frame of the machine in the vertical plane of the forward edge of the table 15 are stop fingers 72 which are carried by the pivotal shaft 73 acted upon by the spring 74, the action of which spring 20 is controlled by the stop pin 75, which construction is provided to permit a slight yielding of said stops 72 under the impact of the forward edge of a sheet of paper therewith, and a return movement carrying 25 the sheet with the forward edge within the desired vertical plane. The shaft 73 does not have movement with the table 15, the stops 72 always occupying the same horizontal position, irrespective of the movements 30 of the table.
- The delivery mechanism of my invention is adapted for use with a high speed printing machine for use with either dry or dampened sheets of paper, although ordinarily the printing is done upon dry sheets. 35 While the manner of delivering the sheets upon the stack carried by the table 15 will ensure a fairly exact stacking, I find in actual practice, that it is desirable, particularly when using dry paper, to provide adjusting or straightening means acting upon 40 each sheet as it is deposited upon the stack and also acting upon adjacent portions of the stack, so as to cause the corresponding edges of the different sheets to lie in the same vertical plane. This straightening mechanism in addition to shifting the sheet whenever necessary, will also tend to relieve 45 the atmospheric pressure beneath each sheet as it is released by the gripper mechanism, so as to ensure its falling perfectly flat upon 50 the top of the stack.
- The straightening mechanism above referred to comprises side plates 76-77 and a rear plate 78, said plates respectively being 55 actuated by means which will simultaneously move them away from the stack as a sheet is being released or approaching the position where it will be released, and will 60 be moved inwardly into engagement with the edges of the stack under spring pressure after the delivery of the sheet, and thus adjust the sheet after it is positioned at the top of the stack and at the same time true up 65 the adjacent portion of the stack. Said plates, like the stops 72, do not have vertical movement with the table, but always occupy a position where they will be operative adjacent the top of the stack irrespective of its height. The actuating means for both side 70 plates 76-77 is the same, so that a description of but one of these mechanisms is essential.
- Carried by each of the plates 76-77 are arms 79-80 slidably mounted in one side 75 frame of the machine, each supported by a guide bracket 80. Each of the rods 79 carries a collar 81 acted upon by a spring 82 which has a normal tendency to thrust the rods 79 and the plate 76 or 77 inwardly 80 of the side frame. Both arms 79 are rigidly secured to a frame 83, which frame also carries a slide 84 having a recessed portion adapted to be engaged by the cam 85 carried by the oscillatory plate 86. The plate 86 is actuated by means of a cam 87 acting upon a bell crank lever 88, one arm of which carries an anti-friction roller co-operating with said cam, and the other arm of which is connected by means of the link 89 with said plate 86. Said link passes through a guide bearing 90 between which and the collar 91 upon said link, a spring 92 acts to normally actuate the plate in a manner to permit the spring 82 to function 95 to impart movement to the plate 77. Corresponding parts having a corresponding function are used in connection with the plate 78, said parts being indicated in the drawings by corresponding reference numerals.
- To ensure a simultaneous inward and outward movement of the rear plate 78, I support this plate from oppositely disposed slides 93 and 94 which are actuated by 100 means of the cranks 95 and 96 carried by the shaft of the plates 86 respectively.
- By a proper design and set of the cams 87, the outward movement of the plates 76, 77 and 78 may be so controlled as to occur 105 substantially simultaneously with the disengagement of the sheet by the gripper mechanism, and the return or inward movement thereof be timed so as to occur immediately following the depositing of the 110 sheet upon the top of the stack. It will be observed that the inward movement of the plates is under the control of springs, so that said plates will automatically adapt 115 themselves to the edges of the stack of sheets.
- The operation of the herein described mechanism is substantially as follows:— 120
- While the press is in operation, the conveyor chains 18 and 19 and the various wires 36 are driven by means of the gear 14, 125 their rate of traverse being the same as the peripheral speed of the impression cylinder from which they receive the printed sheets. As each gripper mechanism reaches its operative relation to the said impression cyl- 130

inder 11, the rollers upon the crank arms 32 will engage the cams 33 and raise the gripper fingers 30 from the co-operating platen 28 to receive the edge of the sheet 5 from the gripper fingers upon the impression cylinder, the fall of said cams 33 permitting the fingers to close under the tension of the springs 31 upon the sheet and thus transfer it from the impression cylinder 10 to said gripper mechanism, and the substantially horizontal top reach of the wires 36.

Thereafter the printed sheet will be carried by said gripper mechanism to adjacent 15 the table 15, the wires 36 supporting the sheet intermediate the chains 18 and 19 until the sheet passes upon the wheels 35, the recessed portions of which wheels will receive the bars 27 and 29 so as to bring the 20 top of the platen substantially flush with the perimeter of said wheels.

The round wires 36 of small diameter, travelling at the same speed as the sheet of paper, will contact with but a very small 25 area of the paper, amounting to practically a lineal contact, and will have no rubbing action thereon which would tend to smut the imprint or permit offsetting upon the carrier mechanism.

30 During the travel of the sheet both surfaces thereof will be exposed in substantially their entirety, to the action of the air thereon so that by having the chains of sufficient length, the ink will be sufficiently dry 35 before it reaches a point above the table 15, to avoid any possible offsetting of any portion of the impression after the sheet has been deposited upon the stack carried by said table.

40 As the gripper mechanism passes upon the horizontal reach of the chains 18 and 19 parallel with and above the table 15, the presser fingers 47 will be elevated to permit the passage of the bars 27 and 29 thereunder.

45 As the rollers upon the arms 32 engage the fixed cams 34, or substantially simultaneously with the actuation of the rod 29 and its gripper fingers as a result of such engagement, the fingers 47 will be moved downwardly rapidly into engagement with the sheet to a point below the plane of said gripper fingers, thus tending to force the sheet toward the top of the stack. Substantially simultaneously with the downward movement of said fingers, the side plates 76 and 77 will be moved toward the opposite side frames of the machine respectively, and the rear plate 78 will be moved outwardly 50 of the table 15, thus affording sufficient clearance at the top of the stack upon the table 15 to avoid the engagement of the edges of the sheet with said plates. Furthermore, the outward movement of the plates 76, 77 and 78 will tend to reduce the

atmospheric pressure between the sheet being delivered and the top of the stack, thus minimizing likelihood of the formation of air pockets which will retard the descent of the sheet.

70 When the forward edge of the sheet is released and disengaged from the gripper fingers 30, it will, through momentum, engage the yieldable stops 72 at the forward edge of the stack, its movement thus being checked without crumpling the edge of the sheet, and a return movement being imparted to the sheet as the fingers resume their normal position, which may or may not bring the sheet in the desired relation 75 to the stack.

Immediately following the delivery of a sheet upon the top of the stack, the cam 87 will be actuated to permit the cam plates 86 to have movement so that the side plates 76 80 and 77 and the rear plate 78 may close upon the stack and true up the sheet just delivered, with those sheets already on the stack, these plates during this movement not only engaging the sheet just delivered, but a number of other sheets adjacent the top of the stack, possibly of a thickness of three or four inches, so as to keep the entire top of the stack perfectly straight and avoid the development of any lateral coefficient of 85 pressure in the entire stack which might result in the bulging of the sheets in, or the toppling of, the stack.

90 It will be noted that the inward movement of the plates 76 and 77 is under the control of the spring 81, and that the same movement of the plate 78 is under the control of the spring 92, so that the pressure exerted by said plates will be sufficiently light to avoid distortion of a sheet while permitting the plates to automatically adjust themselves to the three edges of the stack upon which they respectively act, and thus avoid any such positive application of pressures which would tend to bulge the sheets 95 in the stack.

100 The circumference of the wheels 35 coincides with the distance between succeeding gripper mechanisms so that by providing cams designed and set as shown in the drawings, the presser fingers and the stacking plates will be actuated in perfect synchronism with the printing couple and with the various gripper mechanisms carried by the chains 18 and 19.

105 The table 15 or the top of the stack of sheets thereon should be maintained at a sufficient distance below the plane of movement of the horizontal reach of the gripper chains above the table, to permit the proper functioning of the presser fingers 47, although the flexibility of these fingers will permit them to yield in case they press the sheet being delivered directly upon the top 110 of the stack.

As the height of the stack increases, the hand wheel 61 is used to actuate the worm shaft 58 in a manner to lower the table for a sufficient distance to provide space at the top of the stack for a number of sheets, the practice being ordinarily to lower the table three or four inches at a time so as to permit a thousand or more sheets to be accumulated before it is again necessary to use the hand wheel 61.

The range of vertical movement of the table 15 is sufficient to accommodate many thousands of sheets thereon before it is necessary to remove the stack or any portion thereof from said table.

When a stack has been removed from the table, the gear 63 is made operative in relation to the gear 62 by means of the controlling handle 64 so that with a continued run of the press, the chain and sprocket mechanism 65 will, through the gears 59 and 60, worm shaft 58 and worm gear 57, impart a return rotation to the winches 56 in a manner to rapidly raise the table preparatory to a continued run of the press.

By providing the chain and sprocket mechanism 40, the wires 36 are driven at the same speed as the chains 18 and 19, thus avoiding any possible rubbing action of said wires upon the paper.

The take up roller 41, the links 42 and the set screw 43 are used to prevent the development of slack in said wires 36.

The various guides for the chains 18 and 19 are merely to limit the movement of the chains and the gripper mechanisms carried thereby, to a direct lineal traverse and minimize likelihood of rubbing action due to the sagging or buckling of the chains.

It is not my intention to limit the invention to the precise details of construction shown in the accompanying drawings, it being apparent that such may be varied without departing from the spirit and scope of the invention.

Having described the invention, what I claim as new and desire to have protected by Letters Patent, is:

1. A delivery mechanism for printing machines embodying therein the combination with a printing couple, of a collecting table spaced away therefrom, a conveyer mechanism including therein endless chains, a plurality of platen bars carried thereby, gripper fingers associated with each platen bar, guiding means for said chains consisting of sprocket wheels adjacent said printing couple, sprocket wheels below said first named sprocket wheels and adjacent opposite ends of said table, and intermediate sprocket wheels, whereby said chains have an upper direct reach, a lower return reach and a substantially horizontal reach parallel with, and above, said table, in which last reach the position of said grippers will be

reversed in position as compared with when they are passing along said upper direct reach, actuating means for said gripper fingers operative as said chains are passing from said lower return to said upper direct reach, and as said chains are passing from said reach parallel with the table to said return reach respectively and means whereby lineal traverse is imparted to said chains in synchronism with the peripheral traverse of the members of the printing couple.

2. A delivery mechanism for printing machines embodying therein the combination with a printing couple, of a collecting table spaced away therefrom, a conveyer mechanism including therein endless chains extending from adjacent the printing couple and having a reach thereof extending parallel with and above said collecting table, a plurality of platen bars carried thereby, and gripper fingers associated with each platen bar and adapted to engage the forward edge of a sheet, actuating means for said gripper fingers adjacent the printing couple and adjacent said table, means whereby lineal traverse is imparted to said chains in synchronism with the peripheral traverse of the members of the printing couple, and narrow supports for a sheet positioned between and travelling with said chains below said bars and extending from adjacent the printing couple to adjacent the reach of the chain above said collecting table.

3. A delivery mechanism for printing machines embodying therein the combination with a printing couple, of a collecting table spaced away therefrom, a plurality of platen bars carried thereby, gripper fingers associated with each platen bar, guiding means for said chains consisting of sprocket wheels adjacent said printing couple, sprocket wheels below said first named sprocket wheels and adjacent opposite ends of said table, and intermediate sprocket wheels, whereby said chains have an upper direct reach, a lower return reach and a substantially horizontal reach parallel with, and above, said table, in which last reach the position of said grippers will be reversed in position as compared with when they are passing along said upper direct reach, actuating means for said gripper fingers operative as said chains are passing from said lower return to said upper direct reach, and as said chains are passing from said reach parallel with the table to said return reach respectively, means whereby said table may be lowered with relation to the reach of said chains parallel therewith, and means whereby lineal traverse is imparted to said chains in synchronism with the peripheral traverse of the members of the printing couple.

4. A delivery mechanism for printing machines embodying therein the combination with a printing couple, of a collecting table

spaced away therefrom, a conveyer mechanism including therein endless chains, a plurality of platen bars carried thereby, gripper fingers associated with each platen bar, 5 guiding means for said chains consisting of sprocket wheels adjacent said printing couple, sprocket wheels below said first named sprocket wheels and adjacent opposite ends of said table, and intermediate 10 sprocket wheels, whereby said chains have an upper direct reach, a lower return reach and a substantially horizontal reach parallel with, and above, said table, in which last reach the position of said grippers will 15 be reversed in position as compared with when they are passing along said upper direct reach, actuating means for said gripper fingers operative as said chains are passing from said lower return to said upper 20 direct reach, and as said chains are passing from said reach parallel with the table to said return reach respectively, means whereby said table may be lowered with relation to the reach of said chains parallel therewith, means whereby mechanical power may 25 be applied to said means for lowering the table to rapidly raise the table towards said parallel reach of said chains and means whereby lineal traverse is imparted to said 30 chains in synchronism with the peripheral traverse of the members of the printing couple.

5. A delivery mechanism for printing machines embodying therein the combination 35 with a printing couple, of a collecting table spaced away therefrom, a conveyer mechanism including therein endless chains, a plurality of platen bars carried thereby, gripper fingers associated with each platen bar, 40 guiding means for said chains consisting of sprocket wheels adjacent said printing couple, sprocket wheels below said first named sprocket wheels and adjacent opposite ends of said table, and intermediate 45 sprocket wheels, whereby said chains have an upper direct reach, a lower return reach and a substantially horizontal reach parallel with, and above, said table, in which last reach the position of said grippers will be 50 reversed in position as compared with when they are passing along said upper direct reach, actuating means for said gripper fingers operative as said chains are passing from said lower return to said upper direct 55 reach, and as said chains are passing from said reach parallel with the table to said return reach respectively and a geared connection 60 between the sprocket wheels adjacent the printing couple and one of the members of the printing couple, whereby said chains are driven in synchronism with the peripheral traverse of the members of the printing couple.

6. A delivery mechanism for printing machines embodying therein the combination

with a printing couple, of a collecting table spaced away therefrom, a conveyer mechanism including therein laterally spaced sprocket wheels adjacent the printing couple, and adjacent opposite ends of said 70 collecting table, endless chains passing about said sprocket wheels, said last named sprocket wheels causing said chains to pass in a horizontal reach above said table, a plurality of platen bars, and gripper fingers associated 75 with each platen bar and adapted to engage the forward edge of a sheet, carried by said chains, wheels adjacent the sprocket wheels at the beginning of the horizontal reach of said chains having recesses therein adapted 80 to receive said bars, narrow supports for a sheet between and travelling with said chains below said bars and extending from adjacent the printing couple to about said 85 wheels, actuating means for said gripper fingers adjacent the printing couple and adjacent said table, and a geared connection between the sprocket wheels adjacent the printing couple and one of the members of the printing couple, whereby said chains 90 are driven in synchronism with the peripheral traverse of the members of the printing couple.

7. A delivery mechanism for printing machines embodying therein the combination 95 with a printing couple, of a collecting table spaced away therefrom, means whereby said table may be lowered with relation to the delivery reach of said chains, a conveyer mechanism including therein endless chains 100 extending from adjacent the printing couple and having a reach thereof extending parallel with and above said collecting table, a plurality of platen bars carried thereby, and gripper fingers associated with each platen 105 bar and adapted to engage the forward edge of a sheet, actuating means for said gripper fingers adjacent the printing couple and adjacent said table, straightening devices between the horizontal reach of said chains and said table, and adjacent the edges of said 110 table, adapted to engage the edges of sheets of paper as delivered to said table, means actuating said straightening devices, and means whereby lineal traverse is imparted 115 to said chains in synchronism with the peripheral traverse of the members of the printing couple.

8. A delivery mechanism for printing machines embodying therein the combination 120 with a printing couple, of a collecting table spaced away therefrom, means whereby said table may be lowered with relation to the delivery reach of said chains, a conveyer mechanism including therein endless chains 125 extending from adjacent the printing couple and having a reach thereof extending parallel with and above said collecting table, a plurality of platen bars carried thereby, and gripper fingers associated with each 130

platen bar and adapted to engage the forward edge of a sheet, actuating means for said gripper fingers adjacent the printing couple and adjacent said table, straightening devices between the horizontal reach of said chains and said table, and adjacent the edges of said table, adapted to engage the edges of sheets of paper as delivered to said table, means moving said straightening devices away from the sheets upon said table substantially simultaneously with the delivery of a sheet to said table, means moving said devices toward said sheet after it has been deposited upon the stack upon the table, and means whereby lineal traverse is imparted to said chains in synchronism with the peripheral traverse of the members of the printing couple.

9. A delivery mechanism for printing machines embodying therein the combination with a printing couple, of a collecting table spaced away therefrom, a conveyer mechanism including therein endless chains, a plurality of platen bars carried thereby, gripper fingers associated with each platen bar, guiding means for said chains consisting of sprocket wheels adjacent said printing couple, sprocket wheels below said first named sprocket wheels and adjacent opposite ends of said table, and intermediate sprocket wheels, whereby said chains have an upper direct reach, a lower return reach and a substantially horizontal reach parallel with, and above, said table, in which last reach the position of said grippers will be reversed in position as compared with when they are passing along said upper direct reach, actuating means for said gripper fingers operative as said chains are passing from said lower return to said upper direct reach, and as said chains are passing from said reach parallel with the table to said return reach respectively, presser fingers adapted to have movement across the plane of the horizontal reaches of said chains, means whereby said fingers will be forced toward said table substantially simultaneously with the release of a sheet by gripper fingers carried by said chains, whereby each sheet will be forced toward the stack of sheets upon said table, and means whereby lineal traverse is imparted to said chains in synchronism with the peripheral traverse of the members of the printing couple.

10. A delivery mechanism for printing machines embodying therein the combination with a printing couple, of a collecting table spaced away therefrom, a conveyer mechanism including therein endless chains, a plurality of platen bars carried thereby, gripper fingers associated with each platen bar, guiding means for said chains consisting of sprocket wheels adjacent said printing couple, sprocket wheels below said first

named sprocket wheels and adjacent opposite ends of said table, and intermediate sprocket wheels, whereby said chains have an upper direct reach, a lower return reach and a substantially horizontal reach parallel with, and above, said table, in which last reach the position of said grippers will be reversed in position as compared with when they are passing along said upper direct reach, actuating means for said gripper fingers operative as said chains are passing from said lower return to said upper direct reach, and as said chains are passing from said reach parallel with the table to said return reach respectively, stops adjacent and below the horizontal reach of said chains in a position to be engaged by the forward edge of a sheet when released by said gripper fingers, 75

11. A delivery mechanism for printing machines embodying therein the combination with a printing couple, of a collecting table spaced away therefrom, a conveyer mechanism including therein endless chains, a plurality of platen bars carried thereby, gripper fingers associated with each platen bar, guiding means for said chains consisting of sprocket wheels adjacent said printing couple, sprocket wheels below said first named sprocket wheels and adjacent opposite ends of said table, and intermediate sprocket wheels, whereby said chains have an upper direct reach, a lower return reach and a substantially horizontal reach parallel with, and above, said table, in which last reach the position of said grippers will be reversed in position as compared with when they are passing along said upper direct reach, actuating means for said gripper fingers operative as said chains are passing from said lower return to said upper direct reach, and as said chains are passing from said reach parallel with the table to said return reach respectively, stops adjacent and below the horizontal reach of said chains in a position to be engaged by the forward edge of a sheet when released by said gripper fingers, rectilinearly movable plates upon opposite sides of said stops above said table, a rectilinearly movable rear plate opposite said stops, presser fingers adapted to have movement across the plane of the horizontal reaches of said chains, means whereby said fingers

will be forced toward said table substantially simultaneously with the release of a sheet by gripper fingers carried by said chains, whereby each sheet will be forced to 5 ward the stack of sheets upon said table, actuating means for said plates respectively whereby substantially simultaneously with the downward movement of said presser fingers, said plates will be moved away from 10 the stacked sheets upon said table, and will be moved toward said stacked sheets after each fresh sheet has been deposited upon the stack, and means whereby lineal traverse is 15 imparted to said chains in synchronism with the peripheral traverse of the members of the printing couple.

12. A delivery mechanism for printing machines embodying therein the combination with a printing couple, of a collecting 20 table spaced away therefrom, a conveyer mechanism including therein endless chains extending from adjacent the printing couple and having a reach thereof extending parallel with and above said collecting 25 table, a plurality of platen bars carried thereby, and gripper fingers associated with each platen bar and adapted to engage the forward edge of a sheet, actuating means for said gripper fingers adjacent the 30 printing couple and adjacent said table, stops adjacent and below the horizontal reach of said chains in a position to be engaged by the forward edge of a sheet when released by said gripper fingers, rectilineally 35 movable plates upon opposite sides of said stops above said table, a rectilineally movable rear plate opposite said stops, presser fingers adapted to have movement across the 40 plane of the horizontal reaches of said chains, means whereby said fingers will be forced toward said table substantially simultaneously with the release of a sheet by gripper fingers carried by said chains, whereby each sheet will be forced toward 45 the stack of sheets upon said table, arms carried by said first named plates having a recess therein, a rock shaft, cams carried thereby entering the recesses in said arms respectively, a crank arm carried by said shaft, slides supporting said rear plate, connections between 50 said crank arm and said slides, a cam carried by and rotatable with the sprocket wheels for said chains, a bell crank lever acted upon by said cam, spring-pressed 55 connections between said lever and said rock shaft, said cam being so set that substantially simultaneously with the movement of said presser fingers, said rock shaft will be actuated to impart simultaneous movement to all of said plates away from the stack 60 upon said table, and said parts will be automatically restored to normal substantially simultaneously with the deposit of a sheet upon said table, and means whereby lineal traverse is imparted to said chains in synchronism with the peripheral traverse of the members of the printing couple.

14. A delivery mechanism for printing

whereby lineal traverse is imparted to said 65 chains in synchronism with the peripheral traverse of the members of the printing couple.

13. A delivery mechanism for printing machines embodying therein the combination with a printing couple, of a collecting 70 table spaced away therefrom, a conveyer mechanism including therein endless chains extending from adjacent the printing couple and having a reach thereof extending parallel with and above said collecting table, a plurality of platen bars carried thereby, and gripper fingers associated with each platen bar and adapted to engage the forward edge of a sheet, actuating means for said gripper fingers adjacent the printing couple and adjacent said table, stops adjacent and below the horizontal reach of said chains in a position to be engaged by the forward edge of a sheet when released by said gripper fingers, rectilineally movable plates upon opposite sides of said stops above said table, a rectilineally movable rear plate opposite said stops, presser fingers adapted to have movement across the plane of the horizontal 80 reaches of said chains, a cam carried by and rotatable with a sprocket wheel for said chains, a bell crank lever acted upon thereby, a crank shaft carrying said presser fingers, a spring-pressed pitman connecting 85 said bell crank lever and said rock shaft, said cam being so set as to actuate said bell crank lever substantially simultaneously with the release of said gripper fingers, whereby said presser fingers will be forced toward said table substantially simultaneously with the release of a sheet by the gripper fingers carried by said chains, whereby each sheet will be forced toward the stack of 90 sheets upon said table, arms carried by said first named plates having a recess therein, a rock shaft, cams carried thereby entering the recesses in said arms respectively, a crank arm carried by said shaft, slides supporting said rear plate, connections between 95 said crank arm and said slides, a cam carried by and rotatable with the sprocket wheels for said chains, a bell crank lever acted upon by said cam, spring-pressed connections between said lever and said rock 100 shaft, said cam being so set that substantially simultaneously with the movement of said presser fingers, said rock shaft will be actuated to impart simultaneous movement to all of said plates away from the stack 105 upon said table, and said parts will be automatically restored to normal substantially simultaneously with the deposit of a sheet upon said table, and means whereby lineal traverse is imparted to said chains in synchronism with the peripheral traverse of the members of the printing couple.

14. A delivery mechanism for printing

machines embodying therein the combination with a printing couple, of a collecting table spaced away therefrom, a conveyer mechanism including therein endless chains extending from adjacent the printing couple and having a reach thereof extending parallel with and above said collecting table, a plurality of platen bars carried thereby, and gripper fingers associated with each platen bar and adapted to engage the forward edge of a sheet, actuating means for said gripper fingers adjacent the printing couple and adjacent said table, flexibly supported stops adjacent and below the horizontal reach of said chains in a position to be engaged by the forward edge of a sheet when released by said gripper fingers, rectilineally movable plates upon opposite sides of said stops above said table, a rectilineally movable rear plate opposite said stops, presser fingers adapted to have movement across the plane of the horizontal reaches of said chains, a cam carried by and rotatable with a sprocket wheel for said chains, a bell crank lever acted upon thereby, a crank shaft carrying said presser fingers, a spring-pressed pitman connecting said bell crank lever and said rock shaft, said cam being so set as to actuate said bell crank lever substantially simultaneously with the release of said gripper fingers, whereby said presser fingers will be forced toward said table substantially simultaneously with the release of a sheet by the gripper fingers carried by said chains, and each sheet will be forced toward the stack of sheets upon said table, arms carried by said first named plates having a recess therein, a rock shaft, cams carried thereby entering the recesses in said arms respectively, a crank arm carried by said shaft, slides supporting said rear plate, connections between said crank arm and said slides, a cam carried by and rotatable with the sprocket wheels for said chains, a bell crank lever acted upon by said cam, spring-pressed connections between said lever and said rock shaft, said cam being so set that substantially simultaneously with the movement of said presser fingers, said rock shaft will be actuated to impart simultaneous movement to all of said plates away from the stack upon said table, and said parts will be automatically restored to normal substantially simultaneously with the deposit of a sheet upon said table, and means whereby lineal traverse is imparted to said chains in synchronism with the peripheral traverse of the members of the printing couple.

15. A delivery mechanism for printing machines embodying therein the combination with a printing couple, of a collecting table spaced away therefrom, a conveyer mechanism including therein endless chains a plurality of platen bars carried thereby, gripper fingers associated with each platen bar, guiding means for said chains consisting of sprocket wheels adjacent said printing couple, sprocket wheels below said first named sprocket wheels and adjacent opposite ends of said table, and intermediate sprocket wheels, whereby said chains have an upper direct reach, a lower return reach and a substantially horizontal reach parallel with, and above, said table, in which last reach the position of said grippers will be reversed in position as compared with when they are passing along said upper direct reach, a spring-actuated rock shaft carrying said gripper fingers, a crank arm carried thereby, fixed cams adjacent the printing couple and adjacent said table adapted to be engaged by said crank arm to actuate said gripper fingers adjacent said printing couple and operative as they are about to enter said direct reach and adjacent said table and operative before they leave said horizontal reach above said table, straightening devices between the horizontal reach of said chains and said table, and adjacent the edges of said table, adapted to engage the edges of sheets of paper as delivered to said table, means moving said straightening devices away from the sheets upon said table substantially simultaneously with the delivery of a sheet to said table, means moving said devices toward said sheet after it has been deposited upon the stack upon the table, and means whereby lineal traverse is imparted to said chains in synchronism with the peripheral traverse of the members of the printing couple.

16. A delivery mechanism for printing machines embodying therein the combination with a printing couple, of a collecting table spaced away therefrom, a conveyer mechanism including therein endless chains a plurality of platen bars carried thereby, gripper fingers associated with each platen bar, guiding means for said chains consisting of sprocket wheels adjacent said printing couple, sprocket wheels below said first named sprocket wheels and adjacent opposite ends of said table, and intermediate sprocket wheels, whereby said chains have an upper direct reach, a lower return reach and a substantially horizontal reach parallel with, and above, said table, in which last reach the position of said grippers will be reversed in position as compared with when they are passing along said upper direct reach, a spring-actuated rock shaft carrying said gripper fingers, a crank arm carried thereby, fixed cams adjacent the printing couple and adjacent said table adapted to be engaged by said crank arm to actuate said gripper fingers adjacent said printing couple and operative as they are about to enter said direct reach and adjacent said table and

gripper fingers associated with each platen bar, guiding means for said chains consisting of sprocket wheels adjacent said printing couple, sprocket wheels below said first named sprocket wheels and adjacent opposite ends of said table, and intermediate sprocket wheels, whereby said chains have an upper direct reach, a lower return reach and a substantially horizontal reach parallel with, and above, said table, in which last reach the position of said grippers will be reversed in position as compared with when they are passing along said upper direct reach, a spring-actuated rock shaft carrying said gripper fingers, a crank arm carried thereby, fixed cams adjacent the printing couple and adjacent said table adapted to be engaged by said crank arm to actuate said gripper fingers adjacent said printing couple and operative as they are about to enter said direct reach and adjacent said table and operative before they leave said horizontal reach above said table, straightening devices between the horizontal reach of said chains and said table, and adjacent the edges of said table, adapted to engage the edges of sheets of paper as delivered to said table, means moving said straightening devices away from the sheets upon said table substantially simultaneously with the delivery of a sheet to said table, means moving said devices toward said sheet after it has been deposited upon the stack upon the table, and means whereby lineal traverse is imparted to said chains in synchronism with the peripheral traverse of the members of the printing couple.

17. A delivery mechanism for printing machines embodying therein the combination with a printing couple, of a collecting table spaced away therefrom, a conveyer mechanism including therein endless chains a plurality of platen bars carried thereby, gripper fingers associated with each platen bar, guiding means for said chains consisting of sprocket wheels adjacent said printing couple, sprocket wheels below said first named sprocket wheels and adjacent opposite ends of said table, and intermediate sprocket wheels, whereby said chains have an upper direct reach, a lower return reach and a substantially horizontal reach parallel with, and above, said table, in which last reach the position of said grippers will be reversed in position as compared with when they are passing along said upper direct reach, a spring-actuated rock shaft carrying said gripper fingers, a crank arm carried thereby, fixed cams adjacent the printing couple and adjacent said table adapted to be engaged by said crank arm to actuate said gripper fingers adjacent said printing couple and operative as they are about to enter said direct reach and adjacent said table and

18. A delivery mechanism for printing machines embodying therein the combination with a printing couple, of a collecting table spaced away therefrom, a conveyer mechanism including therein endless chains a plurality of platen bars carried thereby,

operative before they leave said horizontal reach above said table, presser fingers adapted to have movement across the plane of the horizontal reaches of said chains, means

- 5 whereby said fingers will be forced toward said table substantially simultaneously with the release of a sheet by gripper fingers carried by said chains, whereby each sheet will be forced toward the stack of sheets 10 upon said table, and means whereby lineal traverse is imparted to said chains in synchronism with the peripheral traverse of the members of the printing couple.

17. A delivery mechanism for printing machines embodying therein the combination with a printing couple, of a collecting table spaced away therefrom, a conveyer mechanism including therein endless chains, a plurality of platen bars carried thereby, 20 gripper fingers associated with each platen bar, guiding means for said chains consisting of sprocket wheels adjacent said printing couple, sprocket wheels below said first named sprocket wheels and adjacent opposite ends of said table, and intermediate sprocket wheels, whereby said chains have an upper direct reach, a lower return reach and a substantially horizontal reach parallel with, and above, said table, in which last 30 reach the position of said grippers will be reversed in position as compared with when they are passing along said upper direct reach, a spring-actuated rock shaft carrying said gripper fingers, a crank arm carried 35 thereby, fixed cams adjacent the printing couple and adjacent said table adapted to be engaged by said crank arm to actuate said gripper fingers adjacent said printing couple and operative as they are about to enter said direct reach and adjacent said table and operative before they leave said horizontal reach above said table, stops adjacent and below the horizontal reach of said chains in a position to be engaged by the forward 40 edge of a sheet when released by said gripper fingers, presser fingers adapted to have movement across the plane of the horizontal reaches of said chains, means whereby said fingers will be forced toward said table substantially simultaneously with the release of a sheet by gripper fingers carried by said chains, whereby each sheet will be forced toward the stack of sheets upon said table, and means whereby lineal traverse is imparted to said chains in synchronism with the peripheral traverse of the members of the printing couple.

18. A delivery mechanism for printing machines embodying therein the combination with a printing couple, of a collecting table spaced away therefrom, a conveyer mechanism including therein endless chains extending from adjacent the printing couple and having a reach thereof extending parallel with and above said collecting table, a

plurality of platen bars carried thereby, and gripper fingers associated with each platen bar and adapted to engage the forward edge of a sheet, a spring-actuated rock shaft carrying said gripper fingers, a crank arm carried thereby, fixed cams adjacent the printing couple and adjacent said table adapted to be engaged by said crank arm to actuate said gripper fingers adjacent said printing couple and adjacent said table, stops adjacent and below the horizontal reach of said chains in a position to be engaged by the forward edge of a sheet when released by said gripper fingers, rectilineally movable plates upon opposite sides of said stops above said table, a rectilineally movable rear plate opposite said stops, presser fingers adapted to have movement across the plane of the horizontal reaches of said chains, means whereby said fingers will be forced toward said table substantially simultaneously with the release of a sheet by gripper fingers carried by said chains, whereby each sheet will be forced toward the stack of sheets upon said table, actuating means for said plates respectively whereby substantially simultaneously with the downward movement of said presser fingers, said plates will be moved away from the stacked sheets upon said table, and will be moved toward said stacked sheets after each fresh sheet has been deposited upon the stack, and means whereby lineal traverse is imparted to said chains in synchronism with the peripheral traverse of the members of the printing couple.

19. A delivery mechanism for printing machines embodying therein the combination with a printing couple, of a collecting table spaced away therefrom, a conveyer mechanism including therein endless chains extending from adjacent the printing couple and having a reach thereof extending parallel with and above said collecting table, a plurality of platen bars carried thereby, and gripper fingers associated with each platen bar and adapted to engage the forward edge of a sheet, actuating means for said gripper fingers adjacent the printing couple and adjacent said table, stops adjacent and below the horizontal reach of said chains in a position to be engaged by the forward edge of a sheet when released by said gripper fingers, rectilineally movable plates upon opposite sides of said stops above said table, a rectilineally movable rear plate opposite said stops, presser fingers adapted to have movement across the plane of the horizontal reaches of said chains, means whereby said fingers will be forced toward said table substantially simultaneously with the release of a sheet by gripper fingers carried by said chains, whereby each sheet will be forced toward the stack of sheets upon said table, actuating means for said plates respectively 130

whereby substantially simultaneously with the downward movement of said presser fingers, said plates will be moved away from the stacked sheets upon said table, and will be moved toward said stacked sheets after each fresh sheet has been deposited upon the stack, means whereby lineal traverse is imparted to said chains in synchronism with the peripheral traverse of the members of the printing couple, and means whereby said table may be moved downwardly and away from the parallel reaches of said chains, said stops, said movable plates and said presser fingers.

20. A delivery mechanism for printing machines embodying therein the combination with a printing couple, of a collecting table spaced away therefrom, a conveyer mechanism including therein endless chains extending from adjacent the printing couple and having a reach thereof extending parallel with and above said collecting table, a plurality of platen bars carried thereby, and gripper fingers associated with each platen bar and adapted to engage the forward edge of a sheet, actuating means for said gripper fingers adjacent the printing couple and adjacent said table, stops adjacent and below the horizontal reach of said chains in a position to be engaged by the forward edge of a sheet when released by said gripper fingers, rectilinearly movable plates upon opposite sides of said stops above said table, a rectilinearly movable rear plate opposite said stops, presser fingers adapted to have movement across the plane of the horizontal reaches of said chains, a cam carried by and rotatable with a sprocket wheel for said chains, a bell crank lever acted upon thereby, a crank shaft carrying said presser fingers, a spring-pressed pitman connecting said bell crank lever and said rock shaft, said cam being so set as to actuate said bell crank lever substantially simultaneously with the release of said gripper fingers, whereby said presser fingers will be forced toward said table substantially simultaneously with the release of a sheet by the gripper fingers carried by said chains, whereby each sheet will be forced toward the stack of sheets upon said table, arms carried by said first named plates having a recess therein, a rock shaft, cams carried thereby entering the recesses in said arms respectively, a crank arm carried by said shaft, slides supporting said rear plate, connections between said crank arm and said slides, a cam carried by and rotatable with the sprocket wheels for said chains, a bell crank lever acted upon by said cam, spring-pressed connections between said lever and said rock shaft, said cam being so set that substantially simultaneously with the movement of said presser fingers, said rock shaft will be actuated to impart simultaneous movement to all of said plates away from the stack upon said table, and said parts will be auto-

movement to all of said plates away from the stack upon said table, and said parts will be automatically restored to normal substantially simultaneously with the deposit of a sheet upon said table, means whereby lineal traverse is imparted to said chains in synchronism with the peripheral traverse of the members of the printing couple, and means whereby said table may be moved downwardly and away from the parallel reaches of said chains, said stops, said movable plates and said presser fingers.

21. A delivery mechanism for printing machines embodying therein the combination with a printing couple, of a collecting table spaced away therefrom, a conveyer mechanism including therein endless chains extending from adjacent the printing couple and having a reach thereof extending parallel with and above said collecting table, a plurality of platen bars carried thereby, and gripper fingers associated with each platen bar and adapted to engage the forward edge of a sheet, actuating means for said gripper fingers adjacent the printing couple and adjacent said table, flexibly supported stops adjacent and below the horizontal reach of said chains in a position to be engaged by the forward edge of a sheet when released by said gripper fingers, rectilinearly movable plates upon opposite sides of said stops above said table, a rectilinearly movable rear plate opposite said stops, presser fingers adapted to have movement across the plane of the horizontal reaches of said chains, a cam carried by and rotatable with a sprocket wheel for said chains, a bell crank lever acted upon thereby, a crank shaft carrying said presser fingers, a spring-pressed pitman connecting said bell crank lever and said rock shaft, said cam being so set as to actuate said bell crank lever substantially simultaneously with the release of said gripper fingers, whereby said presser fingers will be forced toward said table substantially simultaneously with the release of a sheet by the gripper fingers carried by said chains, and each sheet will be forced toward the stack of sheets upon said table, arms carried by said first named plates having a recess therein, a rock shaft, cams carried thereby entering the recesses in said arms respectively, a crank arm carried by said shaft, slides supporting said rear plate, connections between said crank arm and said slides, a cam carried by and rotatable with the sprocket wheels for said chains, a bell crank lever acted upon by said cam, spring-pressed connections between said lever and said rock shaft, said cam being so set that substantially simultaneously with the movement of said presser fingers, said rock shaft will be actuated to impart simultaneous movement to all of said plates away from the stack upon said table, and said parts will be auto-

matically restored to normal substantially simultaneously with the deposit of a sheet upon said table, means whereby lineal traverse is imparted to said chains in synchronism with the peripheral traverse of the members of the printing couple, and means whereby said table may be moved down-

wardly and away from the parallel reaches of said chains, said stops, said movable plates and said presser fingers.

In witness whereof I have hereunto affixed my signature, this 1st day of February, 1922.

FRANK C. MARQUARDT.
